ABSTRACT OF THE DISCLOSURE

Di- and tri-substituted pyrroles may be prepared by decarbonylating of the corresponding mono- and di-carboxylic acid esters and mono- and di-ketones by warming the esters of ketones with phosphoric acid.

RELATED APPLICATIONS

This application is a continuation-in-part of our co-pending application Ser. No. 468,633 filed June 30, 1965, now abandoned.

FIELD OF THE INVENTION

A novel method of decarbonylation carboxylic acid esters and ketones of pyrroles.

DESCRIPTION OF THE PRIOR ART

Heretofore it has been known to decarboxylate the carboxylic acid esters of di- and tri-substituted pyrroles particularly C-substituted pyrroles. However these methods have been substantially unfeasible for commercial application. In the principal method known to the art, the esters are hydrolyzed and decarboxylated to the tri-substituted pyrroles of Formula A by heating with strong sulfuric acid (3 vols. conc. H_2SO_4 +1 vol. H_2O) on a steam bath until the evolution of CO_2 and the alcohol, e.g., C_2H_5OH when R is C_2H_5- , is completed. In general, this step takes from one to one and one-half hours. (See Formulas I to VI in column 3).

Since the tri-substituted pyrroles and even more so di-substituted pyrroles, are sensitive to oxygen and hot acids, it is customary to carry out the hydrolysis and decarboxylation in an atmosphere of nitrogen or other inert gas. However, even under the most careful working conditions, the yields of the tri-substituted pyrroles in most cases are unsatisfactory. In general, they are less than 50% of theory. The pyrrole is always accompanied by a large amount of resinous by-products (black or red tars) which, in many cases, form the main product of the reaction.

We have found that the formation of these tars is due to the oxidation of the substituted pyrroles which occurs, even in the absence of oxygen, by the oxidative action of the hot sulfuric acid used in the process. Indeed, in working up the reaction mixtures, we have always observed a strong odor of SO_2 which results from the oxidative action of the H_2SO_4 , the latter being reduced in the process.

We have now made the surprising discovery that the

2

formation of the tars can be completely suppressed by eliminating the sulfuric acid and using phosphoric acid (concentration of 60% to 100%) in place thereof. The 85% phosphoric acid of commerce has proved to be an excellent replacement for the sulfuric acid. The phosphoric acid is not only devoid of oxidative action but has the added advantages that the decarboxylation of the esters of Formulae IX and XI occurs at much lower temperatures and at a much faster rate than decarboxylations effected with sulfuric acid. Thus, when using sulfuric acid, temperatures of 100–120° C. and time intervals of one to one and one-half hours are required for completion of the reaction. In contrast thereto, decarboxylations with 85% phosphoric acid usually occur at 65–80° C.; and in most instances, are completed in ten to fifteen minutes.

It was found by Treibs and Schmidt [Ann. 577, 105–115 (1952)] that carboxylic acid esters of pyrroles may be readily decarboxylated by the sequential steps of saponifying the esters by heating with aqueous sodium hydroxide for several hours followed by acidification with acetic acid. It will be readily seen that the process of the present invention which can be carried out in one step in a shorter period of time constitutes a far more commercially viable process than that disclosed by Treibs.

Moreover, attempts were made to carry out the decarboxylation of the carboxylic acid esters by heating the esters under reflux with glacial acetic acid. It was found that such treatment caused no change in the ester whatsoever and the decarboxylation was not observed.

SUMMARY OF THE INVENTION

In the process of the present invention, pyrroles of Formula A are obtained in a high state of purity and in yields of over 80% of pure product in most cases, by the phosphoric acid decarbonylation of the corresponding pyrrole carboxylic acid esters of pyrrolyl ketones.

The compounds of the present invention have the general Formula A

wherein R_2 and R_3 , may be hydrogen, lower alkyl, lower alkenyl, cycloalkyl having a maximum of 8 carbon atoms, phenyl, halophenyl, lower alkoxyphenyl, and benzyl; R_4 and R_5 have the same values as R_2 and R_3 and may additionally be linked together to form an alicyclic ring having a maximum of 8 carbon atoms provided that in the monocyclic system one or two members of the group R_2 , R_3 , R_4 and R_5 are hydrogen, and in the bicyclic system, one member of the group R_2 and R_3 is hydrogen.

The prefix "lower alk." designates a straight or branched carbon chain of 1–6 carbon atoms.

In the general process of the present invention, a pyrrole nucleus having one or two carboxylic acid ester moieties, or keto-moieties substituted therein is heated with concentrated aqueous phosphoric acid. It is to be understood that they may be one or two carboxylic acid moieties or keto-moieties attached to the pyrrole ring itself provided that these moieties are not attached to adjacent carbon atoms. Thus, in the monocyclic system, the carboxylic acid ester, or keto-moieties if monosubstituted may be

at positions 2, 3, 4, or 5 in the ring, where bisubstituted may be at positions 2 and 4, 2 and 5 or 3 and 5, whereas in the bicyclic system, only monosubstitution at positions 2 or 3 is feasible.

PREFERRED EMBODIMENTS

In the preferred modification of the present invention, the starting material utilized is a pyrrole of the following formulae

wherein n is 0, 1, 2 or 3, R is OR_6 or R_6 and R_2 , R_3 , R_4 or R_5 are lower alkyl, for example methyl, ethyl, propyl, butyl, pentyl, or hexyl; lower alkenyl such as vinyl, allyl, butenyl or hexenyl; cycloalkyl, for example, cyclopentyl, cyclohexyl, or cyclobutyl, phenyl, halophenyl, such as fluorophenyl, bromophenyl or chlorophenyl; lower alkoxypyhenyl, such as methoxy-, ethoxy-, propoxy-, or pentoxy-, phenyl or benzyl. R_6 is lower alkyl such as methyl, ethyl, propyl or butyl; phenyl; or benzyl.

The starting material is taken up in approximately ten times its weight of the phosphoric acid. It is preferred to use strong aqueous phosphoric acid of between 60 and 100% by weight, 85% commercial phosphoric acid being the most suitable. The mixture is heated if desired, in an inert atmosphere, preferably nitrogen at between 55° and 120° C. most suitably between 65° and 80° C. for from 5 to 30 minutes preferably for from between 10 to 15 minutes. Where the starting material is a ketone rather than an ester reaction temperatures of between 130° and 145° C. are preferred. The reaction is quenched by pouring the reaction mixture onto ice and neutralizing the resultant aqueous suspension with a base, preferably aqueous ammonia. The decarboxylated pyrrole is then isolated suitably by extracting the aqueous suspension with a suitable water-immiscible organic solvent such as ether. The desired product is then isolated from the solvent in the usual manner.

PREPARATION OF STARTING MATERIALS

A general two-step method for the synthesis of the tri-substituted pyrroles of Formula A consists in the reductive condensation of an α -oximino ketone (VII) with a β -keto-ester (VIII) which results in the formation of ester (IX) in accordance with the following reaction scheme:

A similar method of synthesis (which leads to di-substituted pyrroles) consists in the reductive condensation of an α -oximino- β -ketoester (X) with a β -keto-ester (VIII) with the dicarboxylic acid (XI) ester in accordance with the following reaction scheme:

In the foregoing reaction schemes, R_2 and R_4 have the significance above defined, and R_6 designates, conveniently, a suitable alkyl group, preferably lower alkyl, e.g., methyl, ethyl, propyl, etc., or a phenyl or benzyl group.

This method is also applicable to the formation of compounds of Formulae V and VI. Specific reference is made to the disclosure of tetrahydroindoles and cyclopentenopyrroles at Chem. Abs., vol. 29, col. 4356₈ and 10 vol. 30, col. 8208₅ and 6. Also, to the preparation of the corresponding cycloheptenopyrroles at vol. 54, col. 10898_g.

STATEMENT OF UTILITY

The compounds prepared by the process of the present invention may be converted to the corresponding pyrrol-3-ylketones which are useful as muscle relaxants and sedatives and which may themselves be converted into the corresponding 2-aminoethylpyrrol-3-ylketones which are valuable as tranquilizers and anti-depressants. The processes for converting the compounds produced by the present invention into these desirable compounds of pharmacodynamic activity as well as methods of using them are disclosed in the application of Karl Schoen and Irwin J. Pachter Ser. No. 403,387, now U.S. Pat. No. 3,410,857, filed Oct. 12, 1964, and the continuation application thereof Ser. No. 682,670 filed Nov. 13, 1967, now abandoned.

PREPARATION 1

5-butyl-2,4-dimethylpyrrole

A mixture of 600 ml. of concentrated sulfuric acid and 200 ml. of water was heated on a steam bath in a nitrogen atmosphere; and 100 g. of ethyl 5-butyl-2,4-dimethylpyrrole-3-carboxylate added rapidly thereto with stirring. Heating was continued until the carbon dioxide formation ceased, which took about fifty minutes. The mixture was cooled, poured on ice, neutralized with sodium bicarbonate and the black oily residue taken up in ether. The ether solution was dried, the solvent removed and the residue distilled. The 5-butyl-2,4-dimethylpyrrole distilled at 105–114° C./17–19 mm. Yield: 30 g. (48% of theory).

PREPARATION 2

Diethyl 2,4-dimethylpyrrole-3,5-dicarboxylate 12 g. was refluxed in 100 ml. acetic acid for one hour, the solution poured on ice, the solid which separated filtered, washed with water and dried. There was recovered 11.5 g. of unchanged starting material, M.P. 134°.

The following are examples in accordance with the method of this invention. The temperatures are centigrade.

EXAMPLE 1

5-butyl-2,4-dimethylpyrrole

Ethyl 5-butyl-2,4-dimethylpyrrole-3-carboxylate, 100 g., and 800 ml. of 85% phosphoric acid were stirred and heated in a nitrogen atmosphere. Decarboxylation commenced at 65° and became quite vigorous at 75°. Heating was continued for ten minutes at 90° when the evolution of gas stopped. The mixture was cooled to room temperature, poured on 2 kg. of ice and neutralized with equal parts of ice and ammonia water. The 5-butyl-2,4-dimethylpyrrole separated as an almost colorless oil. It was taken up in ether, dried over magnesium sulfate, the solvent removed and the residue fractionated in vacuo; b_{15} mm. 105–107°; yield, 53 g. (82% of theory).

In accordance with the above procedure but starting with ethyl 5-butyl-3,4-dimethylpyrrole-2-carboxylate, and ethyl 4-methyl-3-cyclopentyl-5-propylpyrrole-2-carboxylate, there is obtained 5-butyl-3,4-dimethylpyrrole and 4-methyl-3-cyclopentyl-5-propyl pyrrole.

5

EXAMPLE 2

5-propyl-2,4-dimethylpyrrole

Ethyl 5-propyl-2,4-dimethylpyrrole-3-carboxylate, 150 g., was decarboxylated in accordance with Preparation 1. 50 g. of the pyrrole, b_{15} mm., 90° was obtained (51% of theory).

When the reaction was carried out in accordance with the method described in Example 1, 93 g. of the starting ester gave a yield of 55 g. of the pyrrole (90% of theory).

EXAMPLE 3

5-ethyl-2,4-dimethylpyrrole

Ethyl 5-ethyl-2,4-dimethylpyrrole-3-carboxylate, 100 g. and 800 ml. of 85% phosphoric acid were heated and stirred under nitrogen at 65-80°. Decarboxylation was completed in ten minutes. On working up the reaction mixture there was obtained 50 g. of 5-ethyl-2,4-dimethylpyrrole (80% of theory) b_{19} mm. 91-92°.

EXAMPLE 4

4-butyl 2,5-dimethylpyrrole

This tri-substituted pyrrole was prepared in accordance with the method of Example 1 from ethyl 4-butyl-2,5-dimethyl-pyrrole-3-carboxylate. Decarboxylation began at 77° and was completed in ten minutes at 82°. From 190 g. of the starting ester, a yield of 100 g. of the pyrrole (78% of theory) was obtained. b_{13} mm. 103°.

EXAMPLE 5

4-propyl-2,5-dimethylpyrrole

This tri-substituted pyrrole was prepared in accordance with the method described in Example 1 from ethyl 4-propyl-2,5-dimethylpyrrole - 3 - carboxylate. Decarboxylation began at 81° and was completed at 84°. From 125 g. of the starting ester, a yield of 66 g. of the tri-substituted pyrrole (82% of theory) was obtained.

EXAMPLE 6

2-benzyl-4,5-dimethylpyrrole

This tri-substituted pyrrole was prepared in accordance with the method of Example 1 from methyl 2-benzyl-4,5-dimethylpyrrole-3-carboxylate (M.P. 115-115.5°). Since the solid ester was insoluble in the phosphoric acid, the mixture had to be heated to 110-115° whereupon the ester melted and decarboxylation proceeded rapidly. After working up the reaction mixture, a solid material was obtained which after repeated crystallizations from 75% ethanol had a melting point of 51-51.5°. From 22.6 g. of the starting ester, a yield of 17 g. (99% of theory) was obtained.

EXAMPLE 7

5-propyl-2,4-dimethylpyrrole

Ethyl 5-propyl-2,4-dimethylpyrrole-3-carboxylate 100 g. was suspended in 800 ml. of 60% phosphoric acid and heated with stirring in a nitrogen atmosphere. The ester liquefied at 103° and at the same time was decarboxylated. Heating was continued at 103-108° for 30 minutes when the evolution of carbon dioxide ceased. The solution was poured on ice, neutralized with ice cold ammonia water, the soil which separated taken up in ether, dried, and after evaporation of the solvent the residue distilled in vacuo; 55 g. of 5-propyl-2,4-dimethylpyrrole. b_{16} mm. 85-88° was obtained (84% of theory).

EXAMPLE 8

2,4-dimethyl-5-phenylpyrrole

To a mixture of 85.8 g. of 1-oximino-1-phenyl-2-propanone and 68.9 g. ethyl acetoacetate in 400 ml. acetic acid was added 85 g. zinc dust in small portions with stirring. The mixture became hot and the temperature rose to 70°. After addition of the zinc, the mixture was refluxed for 45 minutes, then poured on 2 kg. ice. The

6

solid which separated was filtered, washed with water; dried and extracted with cyclohexane. After evaporating the solvent, 93 g. ethyl 2,4-dimethyl-5-phenylpyrrole-3-carboxylate M.P. 119° was obtained.

5 The ester 4.5 g. was heated with 50 ml. of 85% phosphoric acid with stirring. At about 115° the ester melted and decarboxylated within a few minutes. The mixture was quenched in 200 g. ice. A solid separated which was filtered, washed with water, dried and crystallized from hexane. 2,4-dimethyl-5-phenylpyrrole M.P. 74° was obtained; yield 3.2 g. = 100% of theory.

EXAMPLE 9

2,4-dimethylpyrrole

15 The preparation of this pyrrole by decarboxylation of diethyl 2,4-dimethylpyrrole-3,5-dicarboxylate with hot sulfuric acid is described in the book: Die Chemie des Pyrrols, by H. Fischer and H. Orth (Leipzig 1934) vol. I, page 42. Using 200 g. of the ester they obtained 27 g. 20 2,4-dimethylpyrrole, a yield of 32% of theory.

Running the decarboxylation with phosphoric acid we have heated 195 g. ester with 1 liter 85% phosphoric acid with stirring in a nitrogen atmosphere. Decarboxylation began slowly at 80° but due to the high melting point of 25 the ester the reaction proceeded rapidly only at 110-115° and was finished in 30 minutes. After pouring the solution on 3 kg. ice, neutralization with strong ammonia, ether extraction of the pyrrole, drying the ether solution with $MgSO_4$, and evaporation of the solvent, the 2,4-dimethylpyrrole was distilled in vacuo B.P. $_{12}$ mm. 50°. 51.3 g. was obtained, a yield of 66% of theory.

EXAMPLE 10

3-methyl-4,5,6,7-tetrahydroindole

35 Ethyl 3-methyl-4,5,6,7-tetrahydroindole - 2 - carboxylate (100 grams) and 800 ml. of 85% phosphoric acid is heated and stirred under nitrogen at 65° to 80° C. Decarboxylation is completed in 15 minutes. The mixture is 40 cooled and poured onto 2 kg. of ice, neutralized with concentrated aqueous ammonia, the aqueous mixture extracted with ether, the ether dried over magnesium sulfate, filtered evaporated to yield 3-methyl-4,5,6,7-tetrahydroindole.

45 In accordance with the above procedure, but starting with ethyl 3-methyl-4,5-cyclopenteno-pyrrole-2-carboxylate, ethyl 2-methyl-4,5-cyclopentenopyrrole-3 carboxylate and ethyl 2-methyl-4,5-cyclohepteno-pyrrole-3-carboxylate in place of ethyl 3-methyl-4,5,6,7-tetrahydroindol-2-carboxylate, there is obtained the corresponding 3-methyl-4,5-cyclopenteno-pyrrole, 2-methyl - 4,5 - cyclopenteno-pyrrole and 2-methyl-4,5-cyclohepteno-pyrrole.

EXAMPLE 11

2,3,5-trimethylpyrrole

55 2,4,5-trimethylpyrrol-3-yl methyl ketone (62 g.) was dissolved with stirring in 600 mml. of 85% H_3PO_4 and heated in a nitrogen atmosphere to 140° for 30 minutes. After cooling to 60° the solution was poured onto ice, neutralized with aqueous ammonia and the pyrrole extracted with four portions of 200 ml. ether. The combined ether solutions were dried over magnesium sulfate, the solvent evaporated, the residue distilled in vacuo yield 34 g. 2,3,5-trimethylpyrrole (76% of theory) B.P. $_{16}$ 74-76°.

EXAMPLE 12

3-butyl-2,5-dimethylpyrrole

70 4-butyl-2,5-dimethylpyrrol-3-yl methyl ketone (62 g.) was heated in 600 ml. 85% H_3PO_4 for 30 minutes to 135° under nitrogen and worked up as described in the preceding example. There was obtained 40 g. 3-butyl-2,5-dimethylpyrrole (83% of theory) B.P. $_{13}$ 102-106°.

75 It will be understood that the foregoing description of the invention and examples set forth, are merely illustrative of the principles thereof. Accordingly, the appended

claims are to be construed as defining the invention within the full spirit and scope thereof.

We claim:

1. A method of preparing a C-substituted pyrrole of the following Formula A

Formula A

wherein R₂, R₃, R₄ and R₅ may each be hydrogen, lower alkyl having from 1 to 6 carbon atoms, lower alkenyl having from 2 to 6 carbon atoms, cycloalkyl having from 4 to 8 carbon atoms, phenyl, halophenyl, lower alkoxyphenyl having from 1 to 6 carbon atoms, and benzyl, and R₄ and R₅ may additionally be linked together to form an alicyclic ring having from 5 to 7 carbon atoms, provided that when Formula A is monocyclic, one or two members of the Group R₂, R₃, R₄ and R₅ are hydrogen, and when Formula A is bicyclic R₂ or R₃ is hydrogen, which comprises heating a carbonyl compound of the following Formula B with phosphoric acid:

Formula B

wherein R_{2'}, R_{3'}, R_{4'} and R_{5'} may each be selected from the same groups from which R₂, R₃, R₄ and R₅ are selected, and in which one or two non-adjacent moieties selected from the group consisting of R_{2'}, R_{3'}, R_{4'} and R_{5'} are

wherein R is —R₆ or —OR₆ in which R₆ is alkyl having from 1 to 4 carbon atoms, phenyl or benzyl; neutralizing the reaction mixture; and isolating the pyrrole of the foregoing Formula A therefrom.

2. Method of claim 1, wherein the phosphoric acid has a concentration of 60% to 100%.

3. Method of claim 1, wherein the carbonyl compound is ethyl 5-butyl-2,4-dimethylpyrrol-3-carboxylate.

4. Method of claim 1, wherein the carbonyl compound is ethyl 5-ethyl-2,4-dimethylpyrrole-3-carboxylate.

5. Method of claim 1, wherein the carbonyl compound is ethyl 4-butyl-2,5-dimethylpyrrole-3-carboxylate.

6. Method of claim 1, wherein the carbonyl compound is methyl 2-benzyl-4,5-dimethylpyrrole-3-carboxylate.

7. Method of claim 1, wherein the carbonyl compound is propyl 5-propyl-2,4-dimethylpyrrole-3-carboxylate.

8. Method of claim 1, wherein the carbonyl compound is ethyl 2,4-dimethyl-5-phenylpyrrole-3-carboxylate.

9. Method of claim 1, wherein the carbonyl compound is diethyl 2,4-dimethylpyrrole-3,5-dicarboxylate.

10. Method of claim 1, wherein the carbonyl compound is methyl 2,4,5-trimethylpyrrol-3-yl ketone.

11. Method of claim 1, wherein the carbonyl compound is 4-butyl-2,5-dimethylpyrrol-3-yl methyl ketone.

12. The method of claim 1, wherein the decarbonylation is carried out at temperatures of from 55° to 145° C.

13. The method of claim 1, wherein the carbonyl compound of Formula A is an ester and in which the resulting decarboxylation is carried out at temperatures of from 55° to 120° C.

14. The method of claim 1, wherein the carbonyl compound of Formula A is a ketone and in which the resulting decarbonylation is carried out at temperatures of from 30 130° to 145° C.
